US00D834561S

(12) **United States Design Patent** (10) **Patent No.:** **US D834,561 S**
(45) **Date of Patent:** **** Nov. 27, 2018**

(54) **EARBUD**

(71) Applicant: **Oculus VR, LLC**, Menlo Park, CA (US)

(72) Inventors: **Peter Wesley Bristol**, Seattle, WA (US); **Quintin Morris**, Issaquah, WA (US); **James Stocker Webb**, Seattle, WA (US); **Mark Shintaro Ando**, Seattle, WA (US); **David Tao**, Santa Clara, CA (US)

(73) Assignee: **Oculus VR, LLC**, Menlo Park, CA (US)

(**) Term: **15 Years**

(21) Appl. No.: **29/593,251**

(22) Filed: **Feb. 7, 2017**

Related U.S. Application Data

(62) Division of application No. 29/550,158, filed on Dec. 30, 2015, now Pat. No. Des. 783,578.

(51) **LOC (11) Cl.** **14-01**

(57) **CLAIM**

The ornamental design for a earbud, as shown and described.

DESCRIPTION

FIG. 1 is a front isometric view of an earbud showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front isometric view of another embodiment of an earbud showing the new design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

Any broken lines in the Figures are for illustrative purposes only and form no part of the claimed design.

1 Claim, 14 Drawing Sheets

US D834,561 S
